(57) **CLAIM**

The ornamental design for a combined small cell and wireless networking node for mounting on a light pole, as shown and described.

DESCRIPTION

FIG. 1 is a top-front-side perspective view of a combined small cell and wireless networking node for mounting on a light pole showing an embodiment of our new design.

FIG. 2 is a bottom-rear-side perspective view thereof.

FIG. 3 is a top plan view thereof.

FIG. 4 is a bottom plan view thereof.

FIG. 5 is a left side elevational view thereof.

FIG. 6 is a right side elevational view thereof.

FIG. 7 is a rear elevational view thereof.

FIG. 8 is a front elevational view thereof; and,

FIG. 9 is a perspective view of a combined small cell and wireless networking node for mounting on a light pole shown mounted on an environmental light pole fixture.

The broken lines in FIG. 9 depict environment only and form no part of the claim. Stippling shown in the drawings are intended to represent the approximate three-dimensional contour of the design and are not intended to indicate surface decoration.

1 Claim, 8 Drawing Sheets
